UNITED STATES PATENT OFFICE.

GEORGE NEWSUM, OF LEEDS, COUNTY OF YORK, ENGLAND.

TWO-FEED SINGLE-CYLINDER PRINTING-MACHINE.

SPECIFICATION forming part of Letters Patent No. 361,538, dated April 19, 1887.

Application filed September 9, 1886. Serial No. 213,121. (No model.) Patented in England July 3, 1886, No. 8,721.

To all whom it may concern:

Be it known that I, GEORGE NEWSUM, a subject of the Queen of Great Britain and Ireland, residing at Leeds, in the county of York, England, have invented certain Improvements 5 in Two-Feed Single-Cylinder Printing-Machines, (for which I have obtained provisional protection in Great Britain, No. 8,721, dated July 3, 1886,) of which the following is a 10 specification.

The object of this invention is to construct the intermediate frame and bearings for carrying the divided driving-shafts for operating the reciprocating table, so that they are more 15 rigid and not so liable to become twisted with each other as when put together in sections, and to operate the impression-cylinder in a simpler manner without the use of cams, so that it will only revolve one way, and to combine with the latter feeding and delivery apparatus in such a manner that two sheets may 20 be printed with one revolution of the impression-cylinder; and it consists in forming the frame and brackets for supporting the divided 25 shafts in one casting arranged to rest on flanges on the side frames, and fitting to the cylinder driving-wheels and cylinder catches that operate the impression-cylinder in one direction only, and to combine with the latter feeding- 30 boards and delivery apparatus so arranged that two sheets fed from different points may be printed with one revolution of the cylinder.

In the accompanying drawings, Figure 1 35 represents a side elevation of a two-feeder single-cylinder letter-press-printing machine as arranged according to my invention, with one of the side frames removed to show the interior, the impression-cylinder being in section. Fig. 2 is a plan of the machine; Fig. 3, a transverse section through the driving end of the machine; Fig. 4, a sectional detail of the bottom portion of the side frames, intermediate frame, and bearings for supporting 45 the divided shaft; Fig. 5, an end view of the cylinder driving-wheels with a portion cut away to show the driving-catches; Fig. 6, a view showing the movable catch attached to the wheel raised to the position when the cylinder is stationary, and Fig. 7 an end view of 50 the brake pulley and strap.

The side frames, A, are prepared with a projecting flange, B, on the inside of each, which are planed to a straight and level surface, and the intermediate frame, C, along with the brackets C', for supporting the divided 55 shafts D, are cast in one piece with a recess, a, on each side, which are planed to lie on the flanges B of the side frames, A, thereby supporting the frame independently of the 60 bolts A' for securing the same, thereby simplifying the construction and allowing the intermediate frame to be easily removed, and when replaced to occupy the same position.

By casting the brackets C' along with the 65 intermediate frame, C, the journals supporting the divided shafts D cannot twist, therefore reducing the liability of derangement to the connecting crank-pin E, upon which is mounted the connecting-rod F, for giving reciprocating 70 motion to the table G by means of the spur-wheel F', coupled to the said connecting-rod and geared between the fixed toothed rack H and the toothed rack H', secured to the under side of the table G. 75

In order to drive the impression-cylinder J in one direction only without the intervention of cams, I secure to each end of the impression-cylinder J a curved stop, J', one end of which is slightly hollow, the other being curved and 80 pointed, and to each spur-wheel K K, free on the cylinder-shaft and gearing with racks on the table, as in ordinary machines, I secure a stud, and mount thereon a catch, K', held by the spring S in the necessary position against 85 the hollow end of the curved stop J' while driving the impression-cylinder for printing, and on the reversal in the motion of the table G the spring S allows the catch K' to yield on coming in contact with the curved and pointed 90 end, thereby leaving the cylinder stationary until the table moves in the forward direction for printing.

When it is desired that the impression-cylinder J should remain stationary and the table G to reciprocate, I move the handle L into a notch formed in the side frame to the position as shown by Fig. 6, the handle being connected to the shaft L', which extends across the machine, and to which are attached two 100 curved arms, L', which raise the catches K' clear of the fixed curved stops J' by reason of

the small pulleys P coming in contact therewith, thus allowing the table to move and wheels K K to rotate backward and forward, and the impression-cylinder to remain stationary, which is kept rigid by a lever, L³, secured on the same shaft, entering a recess, as shown by Fig. 7, formed in the flange of the brake-pulley M, secured on the cylinder-shaft.

The cylinder J is prepared with two impression-surfaces and two longitudinal openings through the cylinder diametrically opposite each other, in which are fitted grippers similar in construction and operated in a similar manner to those described in English specification No. 1,845, A. D. 1874, for holding the paper to the cylinder during the operation of printing and releasing the same when printed.

The type-forms T and T' are secured to the table G, and the inking of the former accomplished by any of the well-known methods, and on commencing to print the ordinary feed-gages are set to suit the paper and type, and the sheets fed alternately to the impression-cylinder, first from the bottom feed-board, N, and then from the upper feed-board, O. The sheets from the bottom feed-board, N, after receiving the impression from the type T, are removed on the release of the impression-cylinder grippers by the delivery apparatus D', described in English specification No. 632, A. D. 1879, and deposited on the receiving-board N'. The other sheets, taking the impression from type T', are removed on the release of the respective cylinder-grippers by grippers similar to those before mentioned, which are attached to the small revolving cylinder Q, and conveyed by tapes T² to the common delivery-flier R, operated in the ordinary manner by a reciprocating toothed rack gearing with the pinion P', secured on the flier-shaft R'.

When both sheets have been printed, the table G will have traveled to its limit, and on the return-stroke the impression-cylinder J will remain stationary. The catches K', yielding, pass over the curved stops J', in the manner before described, the brake-strap M' gripping the pulley M sufficiently to keep the cylinder firm until the commencement of the return-stroke of the table, when the strap M' will be

clear of the pulley M as soon as the raised portion M² is free of the small pulley V, mounted on the arm Y of the brake-strap.

I form two raised portions, M² and M³, on the circumference of the brake-pulley M, one of which is the means of holding the cylinder J firm when stationary during the return of the table G, and in addition, by M² and M³ operating the brake-strap M', friction is put upon the pulley immediately before the impression is taken, by which means any backlash there may be in the teeth of the racks and wheels K is removed, bringing the teeth faceable and insuring the printing on all the sheets to be of the same "register."

What I claim is—

1. In a printing-machine, the combination, with the side frames, A, having flanges B on the inner side of each piece, of the intermediate bracket-frame, C, having a recess, a, on each side to rest on the flanges B, substantially as described.

2. The combination, with the impression-cylinder J, having a curved stop, J', on each end, and the table G and its racks, of the spur-wheels K K, mounted loosely on the cylinder-shaft and provided with catches K', the pulleys P, springs S, shaft L', having arms L² L', and the lever L, substantially as described.

3. The combination of the impression-cylinder J, the brake-pulley M, secured on the cylinder-shaft and provided with circumferential raised portions M² M³, the pulley V, arm Y, and brake strap M', substantially as described.

4. The combination of the cylinder J, having two impression-surfaces and two longitudinal openings with grippers fitted therein, the table G, provided with type-forms T T', the lower feed-board, N, upper feed-board, O, delivery apparatus D', receiving-board N', cylinder Q, tapes T², and flier R', substantially as described.

In testimony whereof I have signed my name to this specification in the presence of two subscribing witnesses.

G. NEWSUM.
